UNITED STATES PATENT OFFICE.

JOHN H. CLARK, OF POLLOCK, MISSOURI.

STACK PILER AND INCLOSURE.

SPECIFICATION forming part of Letters Patent No. 787,563, dated April 18, 1905.

Application filed May 3, 1904. Serial No. 206,172.

To all whom it may concern:

Be it known that I, JOHN H. CLARK, a citizen of the United States of America, residing at Pollock, in the county of Sullivan and State of Missouri, have invented certain new and useful Improvements in Stack Pilers and Inclosures, of which the following is a specification.

This invention relates to a device for use in pitching or elevating hay, stacking and protecting the said hay, and affording access to the stack in order that the cattle may feed therefrom without wasting the contents of the rick.

The objects of this invention are, first, to provide a novel inclosure for fencing the hay, straw, fodder, or other material and for retaining the same in a rick, permitting feeding therefrom without an opportunity for the cattle to undermine the sides, as so frequently happens with an unprotected rick; second, to provide novel means for delivering the material to the inclosure as the rick is formed, practically doing away with manual labor in the storing of the crops of this character; third, to provide novel means for causing a return of the delivering mechanism with the discharge of its load; and the invention contemplates the provision of an inclosure of the character noted which can be readily assembled and dismantled for the purpose of transporting it, or where the conditions are favorable the inclosure may be moved from place to place in its completed condition, owing to the form of supporting-beams which form a portion of the frame.

Finally, an object of this invention is to produce a device of the character noted which will prove efficient and satisfactory in use and comparatively inexpensive to manufacture and maintain.

With the foregoing and other objects in view the invention consists in the details of construction and in the arrangement and combination of parts to be hereinafter more fully set forth and claimed.

In describing the invention in detail reference will be had to the accompanying drawing, forming part of this specification, wherein in the invention is illustrated by a view in perspective.

In the drawing, A indicates the base-beams or supports, comprising strips of material, preferably wood, having their ends upwardly beveled, as shown at *a*, for the purpose of permitting the said beams to slide over the ground without being impeded by small stones or obstructions or the uneven contour of the field. Resting on or preferably mortised into the beams is a series of transversely-disposed strips B, which might properly be termed "joists," since they form a support for the contents of the inclosure. The end strips B and certain of the intermediate strips have cleats *b* pivoted to them through the medium of the pivots *b'*, which may be in the form of bolts, though I do not wish to be limited in this particular. The cleats *b* embrace on two sides the posts C, to which the side rails *c* are secured by bolts *d* or by any other suitable means. By reason of the pivoted connection of the cleats with the strips B it will be apparent that the side panels are capable of being swung inwardly for the purpose of causing the said panels and the whole device to occupy a small space in shipping or storing. The lower ends *B*² of the posts C are rounded, so as to prevent any binding of the parts when being folded. The side panels are held rigid when the parts are in operative position by the end rails E, which are secured to the end posts by bolts or otherwise. It will be understood that both ends of the panels are to be provided with end rails, though the rails are illustrated on but one end in the drawing. The rails for the opposite end are omitted for the purpose of showing the conditions and positions of the parts prior to their application.

The loading attachment may be stationed on either side of the frame and is attached thereto by means of the cleats F, which are secured to the strips B and extend outwardly therefrom. The standards G form a part of the loading mechanism, and the ends thereof are anchored between the cleats F and secured thereto by the bolts *f* or otherwise. The standards G are braced at their upper ends through the medium of the braces H, which extend from the upper ends of the standards to the posts C. Arms *l* are pivoted between

the cleats F and carry on their outer ends a rake-head J, which may be of any ordinary construction, preferably the head removed from an ordinary horse-rake. The means for oscillating the arms comprises a flexible connection and pulleys arranged in the following manner, viz: Blocks K K' are secured to a lower side rail near the standards, and pulleys k k' are mounted in said blocks. Pulleys L and L' are provided at the upper ends of the standards, while blocks M and pulleys m are secured at the outer ends of the arms. The flexible connection N is strung through the hole n of one standard, out over the pulley m of one arm, then back over the pulley L on the upper end of the standard, then extending down through the pulley k, then extending to the other pulley, k', then extending upward to the pulley L' of the other standard, out over the pulley m on the other arm, and back through an aperture similar to the aperture n of the standard. The ends of the rope are knotted, as at P, or otherwise anchored to prevent their slipping through the holes n. Thus by a pull on the center P' of the flexible connection the arms are elevated, and the arms are returned to the position shown in the drawing by the spring Q, anchored to the ground, as shown at R, and having a rope S connected to the head of the carrier. A single rope N is thus utilized for operating the arms.

The construction, operation, and advantages will, it is thought, be understood from the foregoing description, it being noted that various changes may be resorted to in the proportions and details of construction for successfully carrying the invention into practice without departing from the scope thereof.

Having fully described the invention, what I claim as new, and desire to secure by Letters Patent, is—

1. In a stacking device, a suitable inclosure having its two sides hinged, standards suitably supported with relation to the inclosures, arms pivoted to the inclosures, a head carried by the opposite ends of the arms and means for oscillating the said arms.

2. In a stacking device, suitable base-bars having beveled ends, strips extending transversely of the supports, posts pivotally connected to the strips, rails secured to the posts,

standards suitably anchored with relation to the inclosure-arms pivoted with relation to the standards, pulleys on the outer ends of the arms, a head carried by the arms, pulleys near the tops of the standards, pulleys in fixed relation to the bottoms of the standards, and a flexible connection strung through the pulleys, whereby a single length of material operates the two arms, substantially as described.

3. In a stacking device, a suitable inclosure comprising a base, pivoted side panels and suitable end panels, standards anchored with relation to the side panels, pulleys near the bottoms of the standards, pulleys mounted at the tops of the standards, arms pivoted with relation to the bottoms of the standards, pulleys on the outer ends of the arms, a head carried by the arms, a flexible connection strung through the pulley on the end of one arm and extending back to the pulley at the top of the corresponding standard, then extending down to the pulley near the bottom of the standard, then extended across approximately horizontally to the pulley near the base of the second-mentioned standard, then extended upward to the pulley at the top of the second-mentioned standard and then run out over the pulley on the opposite arm and back through the said standard and anchored, substantially as described.

4. In a stacking device, a suitable inclosure having its two sides hinged, arms pivoted to the inclosure, and adapted to rest normally on the ground, a head carried by the arms, means for raising said arms and head from the ground and automatic means for returning the same to their normal positions.

5. In a stacking device, a suitable inclosure, arms pivoted to the inclosure and adapted to rest normally on the ground, a head on the arms, a connection secured at one end to the head, its opposite end being anchored to the ground, said connection embodying a spring, as and for the purpose described.

In testimony whereof I affix my signature, in the presence of two witnesses, this 25th day of April, 1904.

JOHN H. CLARK.
